CLAIM

The ornamental design for a shooting sports hat, as shown and described.

DESCRIPTION

FIG. 1 is a top perspective view of a shooting sports hat in accordance with a first embodiment;

FIG. 2 is a front view thereof;

FIG. 3 is a side view thereof;

FIG. 4 is a bottom perspective view thereof;

FIG. 5 is a top perspective view of a shooting sports hat in accordance with a second embodiment;

FIG. 6 is a front view thereof;

FIG. 7 is a side view thereof; and,

FIG. 8 is a bottom perspective view thereof.

The head and neck of a person shown in broken lines in the drawings illustrate the environment in which the design is used, and form no part of the claimed design.

My design is characterized as a shooting sports hat, with an integrated eye patch, to obstruct the vision of one eye of the wearer.
